DESIGN FOR A FLASHLIGHT OR SIMILAR ARTICLE

Sidney Bersudsky, Sidney, Nova Scotia, Canada

Application June 3, 1947, Serial No. 139,425

Term of patent 7 years

(Cl. D48—25)

To all whom it may concern:

Be it known that I, Sidney Bersudsky, a subject of the King of Great Britain, residing in the city of Sidney, in the Province of Nova Scotia, Canada, have invented a new, original, and ornamental Design for a Flash Light or Similar Article, of which the following is a specification, reference being had to the accompanying drawing, forming a part thereof.

In the drawing:

I claim:

The ornamental design for a flash light or similar article, substantially as shown.

SIDNEY BERSUDSKY.
